DESIGN FOR A FLOOR PANEL

Stephan Kutchar, Grass Valley, Calif.

Application February 4, 1936, Serial No. 60,981

Term of patent 7 years

To all whom it may concern:

Be it known that I, Stephan Kutchar, a citizen of the United States, residing at Grass Valley, in the county of Nevada and State of California, have invented a new, original, and ornamental Design for a Floor Panel, of which the following is a specification, reference being had to the accompanying drawing, forming part thereof.

Figure 1 is a top plan view of a floor panel showing my new design.

Figure 2 is a view in side elevation thereof.

Figure 3 is an elevational view, looking at the invention at right angles as compared to Figure 2.

I claim:

The ornamental design for a floor panel as shown.

STEPHAN KUTCHAR.
